STOVE

Filed March 26, 1930

UNITED STATES PATENT OFFICE

LOUIS H. GEURINK, OF EAST CLEVELAND, OHIO, ASSIGNOR TO ERIEZ STOVE & MANUFACTURING COMPANY, OF ERIE, PENNSYLVANIA, A CORPORATION OF PENNSYLVANIA

STOVE

Application filed March 26, 1930. Serial No. 438,950.

In stove constructions it is very desirable to enamel the face surfaces of the stove. This enamel is more or less fragile and small defects in any part of the enamel result in the discarding of the part on which the enamel is placed. This breakage, or injury very often happens in shipment and where the enamel is placed directly on the stove frame it means a taking down of the stove and a re-assembly at the point where the stove is received, or in other words, by the dealer on the job. The present invention is designed to simplify the finishing of the faces of stoves both with regard to cheapness in the original assembly of the stove and also with a view of simplifying the means whereby injured or defective enamel parts may be replaced. Features and details of the invention will appear from the specification and claims.

A preferred embodiment of the invention is illustrated in the accompanying drawings as follows:

Fig. 1 shows a front elevation of the stove.
 25 Fig. 2 a section of the line 2—2 in Fig. 1.
 Fig. 3 a section on the line 3—3 in Fig. 1.
 Fig. 4 a section on the line 4—4 in Fig. 1.
 Fig. 5 a perspective view of one of the securing bolts for securing the face plates to the stove.

Fig. 6 an enlarged view of one of the corners of the oven frame.

Fig. 7 a section on the line 7—7 in Fig. 6.
 35 Fig. 8 a perspective view of one of the corner posts in the mitered corner structure shown in Fig. 6.

Fig. 9 a section on the line 9—9 in Fig. 6.
 40 1 marks the stove frame, 2 the door frame forming a part of the stove frame, 3 the upper oven door, and 4 the lower oven door. The door frame has a face bar 5 extending around it, an inward flange 6 terminating in a lateral flange 7 forming the door jamb. The face bar 5 is ribbed at its outer edge having an outwardly faced rib 8 and an inwardly faced rib 9. The side of the stove is provided with a sheet metal plate 10 having an inturned flange 11 engaging the edge of the flange 9.

50 A finish plate 12 has an inturned flange

13 at its outer edge which covers the edge of the bar 5 engaging the corner of the stove side 10, or top. The inner edge of the finish plate 12 has an inturned flange 14 and a return flange 15 extending from the inturned flange. The inturned flange rests on the face bar 5 and has its inner edge spaced from the face bar 5, as clearly shown in Fig. 4. A bolt 16 has a large head 17, one side of which engages the inturned flange 5. The bolt extends through the face bar and through the inturned flange 11 on the side, or top plate 10. A wing nut 18 is screwed on the bolt on the inside of the flange 11. As this is screwed up the finish plate is clamped with spring-pressed engagement with the face bar 5 and at the same time the side, or top plate of the stove is secured to the face bar, or frame. The ends of the finish plates 5 are mitered, but it is difficult to so finish the edges of the plates with enamel as to make a finished appearance. I, therefore, prefer to provide at the mitered edges of the plates a corner plate 19 which forms a rib in the corner and aids in the finish. This corner plate has flanges 20 extending each side of it, these flanges resting at their inner ends of the return flanges 15 of the adjacent plates. The outer end of the plate 19 is cut away on its under side and thus forms an extension 22 which rests on the rib 8 of the face bar. In this way the corner plate is clamped in position at the same time that the finish plates are clamped in position by the bolts 16. It will be understood that there are a series of the bolts 16 extending along the frame at intervals so as to securely clamp the finish plates.

A somewhat similar finish plate 24 is provided for the bottom bar 23 of the stove frame. This has the inturned beveled flange 25 at the bottom engaging the bottom bar 23, an inturned flange 26 and a return flange 27 corresponding to the flanges 14 and 15. Bolts 28 extend through the bar 23 and the heads of these bolts engage the return flange 27 and secure it with spring pressure against the bottom bar. Corner plates 29 are provided at the corners of the bar and bolts 30 extend from the corner

plates through the corner of the bar 23 and are secured by wing nuts 31. In this way the finish plates may be readily secured in place as an original assembly in the stove, 5 may be readily finished in a comparatively small unit so that any defect leads to a very small amount of discard and if there is any injury in transit, or otherwise, the replacement of the finish can be very readily accomplished by the receiver of the stove.

What is claimed as new is:—

1. In a stove, the combination of a stove frame having a face bar; a finish plate for the bar comprising a face plate, an inturned flange, and a return flange extending from the inturned flange; and a bolt operating on the return flange clamping it to the bar.
2. In a stove, the combination of a stove frame having a face bar; a finish plate for the bar comprising a face plate, an inturned flange, and a return flange extending from the inturned flange engaging the bar and the opposite edge of the return flange being spaced from the bar; and a bolt engaging 25 the spaced edge of the bar and clamping the finish plate on the bar.
3. In a stove, the combination of a stove frame having a face bar; a finish plate for the bar comprising a face plate, inturned flanges at the edge of the face plate engaging the bar, and a return flange extending from one of the inturned flanges; and a bolt 30 engaging the return flange clamping the finish plate to the bar.
4. In a stove, the combination of a stove frame having a face bar; a finish plate comprising a face plate, inturned flanges at its edges engaging the bar, and a return flange extending from one of the inturned flanges, 40 the inner edge of the return flange being spaced from the bar; and a bolt engaging the inner edge of the return flange and clamping the finish plate on the bar.
5. In a stove, the combination of a stove frame having a face bar forming a corner; finish plates at each side of the corner, each 45 finish plate comprising a face plate, an inturned flange, and a return flange extending from the inturned flange; bolts operating on the return flanges clamping the finish plates on the bar; a corner plate between the adjacent edges of the finish plates; and means for securing the corner plate in place.
6. In a stove, the combination of a stove frame having a face bar forming a corner; finish plates at each side of the corner, each 55 finish plate comprising a face plate, an inturned flange, and a return flange extending from the inturned flange; bolts operating on the return flanges clamping the finish plates on the bar; and a corner plate between the adjacent edges of the finish plates, said corner plate having flanges extending under the face plates.
7. In a stove, the combination of a stove

frame having a face bar forming a corner; finish plates at each side of the corner, each finish plate comprising a face plate, an inturned flange, and a return flange extending from the inturned flange; bolts operating on the return flanges clamping the finish plates on the bar; and a corner plate between the adjacent edges of the finish plates, said corner plate having flanges extending under the face plates and resting on the return flanges.

8. In a stove, the combination of a stove frame having a face bar formed with a corner; finish plates for the bar, each plate comprising a face plate having an inturned flange and a return flange extending from the inturned flange, the adjacent ends of the finish plates at the corner being mitered; a corner plate between the mitered ends and engaging said ends; and means for securing the corner plate.

9. In a stove, the combination of a stove frame having a face bar formed with a corner; finish plates for the bar, each plate comprising a face plate having an inturned flange, and a return flange extending from the inturned flange, the adjacent ends of the finish plates at the corner being mitered; and a corner plate between the mitered ends and engaging said ends, said corner plate having flanges extending under the corner plate.

10. In a stove, the combination of a stove frame having a face bar formed with a corner; finish plates for the bar, each plate comprising a face plate having an inturned flange, and a return flange extending from the inturned flange, the adjacent ends of the finish plates at the corner being mitered; and a corner plate between the mitered ends and engaging said ends, said corner plate having flanges extending under the corner plate and resting on the return flange.

11. In a stove, the combination of a stove frame having a face bar forming a corner, the face bar having an outwardly extending rib at one edge; finish plates arranged on said bar, said finish plates each having an inturned flange on one edge engaging the edge of the bar opposite the rib and a return flange extending from the inturned flange, said finish plates having mitered corners at their adjacent ends; and a corner plate arranged in the corner, said corner plate having flanges extending under the finish plates, the flanges being cut away at the ribbed end permitting the extension of the corner plate to rest on the rib.

12. In a stove, the combination of a stove frame having a face bar forming a corner piece, the face bar having an outwardly extending rib at one edge; finish plates arranged on said bar, said finish plates each having inturned flanges on one edge engaging the edge of the bar opposite the

rib, and a return flange extending from the inturned flange, said finish plates having mitered corners at their adjacent ends; and a corner plate arranged in the corner, said corner plate having flanges extending under the finish plates, the flanges being cut away at the ribbed end permitting the extension of the corner plate to rest on the rib, the inner ends of the flanges resting on the inturned flanges.

5 10 In testimony whereof I have hereunto set my hand.

LOUIS H. GEURINK.
